C. P. EISENHAUER

PRESSURE SWITCH

Filed Dec. 5, 1925

INVENTOR
CHARLES P. EISENHAUER,
BY *Paulmin* *Paulmin*,
ATTORNEYS.

UNITED STATES PATENT OFFICE.

CHARLES P. EISENHAUER, OF DAYTON, OHIO, ASSIGNOR TO THE DURO COMPANY, OF DAYTON, OHIO, A CORPORATION OF OHIO.

PRESSURE SWITCH.

Application filed December 5, 1925. Serial No. 73,355.

My invention relates to pressure switches.

It is the object of my invention to provide a pressure switch in which the pressure for actuating the switch in one direction during 5 one portion of the movement of the switch will be greater than in the other direction.

It is my object to provide a pressure-operated switch which will have a cooperating yielding means of different characteristics 10 for giving a different resistance in different operations of the switch stroke.

It is a further object to provide a switch of the pressure type which is adapted to make and break electrical contact depending 15 upon the pressure exerted thereon, and depending upon the resistance imparted to the switch, which, in turn, depends upon the operation of the stroke in which the resistance is supplied.

20 Referring to the drawings.

Figure 1 is a section through the switch; Figure 2 is a plan view of the switch.

With reference to the drawings in detail, 25 1 is a passageway for the introduction of the gas, which is under pressure and which is introduced through the usual pipe line coupled by an internally-threaded sleeve mounted at 2 on the sleeve 3 of the end 4 of the switch. This end 4 is mounted on the 30 switch chamber 5 by the screws 6 and is welded thereto by the gasket 7.

On this end wall 4 is mounted a metal bellows 8 which is connected at its free end to a cup 9 that is, in turn, attached to the plunger 10. The gas is contained within the passageway 1 and the chamber 11 formed by the wall 4, the bellows 8 and the cup 9. The variation in pressure in this chamber will actuate the plunger 10. The plunger 10 is supported in the bearing sleeve 12 which, in turn, is threaded within a tubular portion 13 of the cup 5. Within this bearing sleeve 12 is a helical spring abutting against it, which is designated 14. The 40 other end of this helical spring fits against a collar 15 which is held on the other side by an annular internally-extending ring 16 formed on the inside of the sleeve 17. A groove 18 is formed on the plunger 10 in which is carried a ring 19. This ring 19 abuts against a second loose collar 20 carried 45 on the shaft, one side of which engages with

the annular ring 16 and the ring 19, and the other side of which engages with a relatively heavy helical spring 21. The other 55 end of this helical spring is carried within the bearing collar 22 which serves to support that end of the spring and also to support the end of the shaft 10.

The collar 22 is threaded at 23 within the 60 sleeve 17. The free outside end of the plunger 10 has connected thereto by a pin 24 a collar 25 which contains a groove 26. This groove is engaged freely by a depending arm 27 pivoted at 28 on a bracket 29 and forming one arm of a bell crank, the other arm of which is designated 30. The arm 30 terminates in a jaw 31 between the arms of which transversely is projected a pin 32 carried on a lever 33 pivoted at 34 on a bracket 35. This bracket is carried on the sleeve 17. The other end of this lever 33 has pivoted thereto at 36 a plunger 37. This plunger is surrounded by a small 75 helical spring 38, one end of which engages with a shoulder 39 on the plunger, and the other end of which engages within a right angle projection 40 through which the pin 37 projects. This right angle projection 40 is formed as a part of the plate 41 pivoted 80 on the bracket 35 at 42. Thus, this plate is carried up or down and serves as a contact plate for engaging with a contact head 43 on a cable 44.

When the pressure is applied in the chamber 11, the plunger 10 is carried forward 85 with the ring 19 which picks up the ring 20 and operates against the pressure of the heavy helical spring 21.

When this resistance is overcome, the bell 90 crank is operated, the lever 33 is moved about its pivot 34 and the contact plate 41 engages with the contact head 43 closing the circuit of the motor which serves to change, through suitable mechanism, such as a pump, 95 the condition of pressure in the chamber 11.

When this pressure condition is changed to a suitable degree, the spring 21 returns the plunger 10 to a point where the ring 20 100 engages the shoulder 16 where it ceases to function and the further movement of the plunger is against the resistance of the relatively light spring 14 which is caused to be compressed by the movement of the plunger

10 with the ring 19 working against the collar 15 which has now been picked up by the ring 19.

The reduction of pressure in the chamber 5 11 as a result thereof permits the plunger 10 to move toward the bellows end to such an extent that the bell crank will be operated and the circuit broken, thus cutting off the motor.

10 The light spring 14 resists this movement toward the bellows end of the plunger 10 in order that the metal bellows 8 shall not be unduly compressed.

It will be understood that this switch is 15 adapted in a typical installation to work on six inches of vacuum and eighteen pounds of pressure.

It will be understood that I desire to comprehend within my invention such modifications as may be necessary to adapt it to varying conditions and uses.

Having thus fully described my invention, what I claim as new and desire to secure by Letters Patent, is:—

25 1. In a pressure switch, a pressure chamber, a plunger moved thereby, and a switch adapted to control means for regulating the pressure in the pressure chamber operated by said plunger, yielding means on either 30 side of a shoulder on said plunger, a shoulder on said plunger, said yielding means being adapted to be actuated when the shoulder passes the neutral point of rest of said plunger, said springs being adapted to resist 35 the closing of the switch in one direction and to resist the compression of the pressure chamber in the other direction.

2. In a pressure switch, a pressure chamber, a plunger moved thereby, and a switch 40 adapted to control means for regulating the pressure in the pressure chamber operated by said plunger, yielding means on either side of a shoulder on said plunger, a shoulder on said plunger, said yielding means being adapted to be actuated when the shoulder passes the neutral point of rest on said plunger, said springs being adapted to resist the compression of the pressure chamber in the other direction, yielding means resisting 45 the increase of pressure in the pressure chamber being heavier than the yielding means resisting the collapse of the pressure chamber due to the vacuum.

3. In a pressure switch, a pressure chamber having fixed ends and collapsible walls, a plunger attached to one of said ends, a switch actuated by said plunger for controlling the operation of apparatus to vary the pressure in the pressure chamber, and 55 yielding means to resist the movement of the plunger in either direction from the normal condition of the plunger and the pressure chamber, said yielding means for resisting the closing of the switch due to the 60 expansion of the pressure chamber under

pressure being greater than the resistance to the collapse of the pressure chamber and the opening of the switch.

4. In a pressure switch, a housing, a sleeve for said housing, said housing being formed 70 into a cup, a wall mounted on said cup to close it, said wall having a passageway for the introduction of pressure or the creation of a vacuum, a second chamber formed within the first chamber in the cup having a collapsible wall, one end of which abuts against the cover of the cup and the other end of which is attached to a head mounted on a plunger, a head, a plunger adapted to reciprocate in said sleeve, means for guiding 80 said plunger in said sleeve, yielding means surrounding said plunger, the free ends of which engage the means for supporting the plunger, and the other ends of which engage 85 sliding collars on said plunger, sliding collars and a shoulder on said plunger for engaging said collars alternately, and a shoulder on the interior of said sleeve for limiting the movement of said yielding means, and a switch connected to the end of said plunger 90 adapted to be operated thereby.

5. In a pressure switch, a pressure chamber having a collapsible wall and a movable end, a plunger connected to the movable end, yielding means alternately compressed by 95 said plunger, means on said plunger for alternately engaging with said yielding means, and a switch adapted to be operated by said plunger, said yielding means being of greater strength to resist the movement of the 100 plunger when pressure increases in the pressure chamber than the yielding means which resist the movement of the switch when a vacuum is created in the pressure chamber.

6. In a pressure switch, a casing formed like a cup having a tubular member communicating therewith, a cover for said cup having a passageway therein communicating with a pressure chamber formed within said cup, a metal bellows wall for said pressure 110 chamber, a head carried on said wall for moving therewith, a plunger connected to said head, caps threaded in either end of said tubular member adapted to support said plunger, a fixed ring carried on said plunger, loose rings carried on said plunger on either side of the fixed ring, helical springs adapted to be engaged by said loose rings, their free ends resting in said cups threaded in the tubular member, a bell crank having one arm connected to said plunger, and the other end to a switch, a switch, and yielding means adapted to snap said switch into and out of operative position.

7. In a pressure switch, a switch controlling a circuit, a bellows communicating with the pressure line, a plunger connected to the bellows, yielding means cooperating with said plunger to resist its movement in either direction, means to independently adjust the 115

respective yielding means, a fixed abutment on said plunger between said yielding means, a sliding abutment on said plunger on either side of the fixed abutment engaging with said yielding means and adapted to engage with said fixed abutment, said sliding abutments being of greater diameter than the

fixed abutment and a stop adapted to engage said sliding abutments but not to engage the fixed abutment on the plunger.

In testimony whereof, I affix my signature.

CHARLES P. EISENHAUER.
